UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

MEANS AND METHOD FOR SIGNALING.

Application filed September 5, 1919. Serial No. 321,889.

To all whom it may concern:

Be it known that I, KENNETH S. JOHNSON, a citizen of the United States, residing at Jersey City, in the county of Hudson, State of New Jersey, have invented certain new and useful Improvements in Means and Methods for Signaling, of which the following is a full, clear, concise, and exact description.

10 This invention relates to a telephone system and a method of operating the same which is especially adapted to environments where there may be considerable disturbing noise at either or both of the substations, 15 and the principal object in view is to secure maximum or relatively high transmission efficiency over a line of substantial length in connection with the complete elimination of interference with the receiver by the transmission energy originating at the same station,—that is to say elimination of "side tone."

The invention includes more particularly a three-wire line circuit whose essential 25 characteristic is that the transmission of telephonic currents in one direction is effected by only two of the three wires which, for convenience, may be referred to as the "outside" wires, while in the other direction it is effected over these same two wires, acting in 30 parallel for one side of the line and over the third or "neutral" wire or conducting path, acting for the other side.

The invention further includes such a relation 35 of the substation apparatus to the wires of the line circuit as will insure the distribution of the line constants symmetrically among the three wires, thereby effecting perfect balance between the limbs of the 40 line during transmission in either direction.

Thus, the two outside wires are connected at their ends by impedance elements and the neutral conducting path has a connection with each impedance element in such relation 45 that the impedance between said path and one of the outside wires is equal to the impedance between said path and the other outside wire; and the receiver of one station and the transmitter of the other station are 50 electrically associated with the neutral wire, while the transmitter of the first station and the receiver of the second station are electrically associated with the two outside 55 wires in such manner as to maintain the balance of the lines and to insure that the re-

ceiver of the transmitting station will not be affected by the energy originating at that station. The circuit arrangements are preferably, although in most cases not necessarily, such as to insure that there will be no 60 transmission losses due to the passage of voice currents through the transmitter of the receiving station.

Where all three wires are used for the transmission of energy there is less attenuation loss with consequently more effective transmission in that direction than where the transmission is effected in the other direction over the outside wires. For lines of short length this characteristic is immaterial. For lines of considerable length a substantial advantage may be realized by arranging the circuit so that the transmission over the three wires will be from the 70 station whose transmitting efficiency, under 75 normal conditions, is the lower.

While the substation sets are not connected in the same manner at the two ends of the line they may, in most instances, consist of identically the same apparatus. Each 80 set may consist (1) of a three-terminal receiver and a two-terminal transmitter or, (2) a three-terminal transmitter and a two-terminal receiver or, (3) a two-terminal transmitter and a two-terminal receiver, one 85 or both associated with an induction coil.

Figs. 1 to 12 of the accompanying drawings are diagrams showing variations, as regards details of the line circuit, the substation circuits and the connection of the 90 substation sets at the two ends of the line, in a system in which the essential features of the invention are incorporated.

Fig. 1 illustrates a line circuit as above described in connection with the preferred 95 arrangement of substation sets and may be regarded as typical. The line circuit comprises the outside wires 1 and 2 connected at their ends by the windings 3 and 4 of induction coils, and the neutral wire 5 the ends of 100 which are connected at the middle points of said windings. At both stations the transmitters and receivers are in local circuits inductively related to the line circuit. At station A the transmitter is in circuit with the 105 supply battery 6 and the winding 7 of an induction coil which is completed by the winding 3 in the line circuit; and the receiver is in another circuit with the winding 8 of an induction coil which is completed by 110

6 a winding 9, serially arranged in the wire 5. At station B the transmitter is in circuit with the supply battery 10 and the winding 11 of an induction coil which is completed by 11 a winding 12, serially arranged in the wire 5, and the receiver is in another local circuit with the winding 13 of an induction coil which is completed by the winding 4 in the line circuit.

- 10 When A is the transmitting station, the current induced in the coil 3 flows over the wire 1 through the coil 4 and back through the wire 2. Since the impedance between the wire 5 and either of the wires 1 or 2 is 15 equal to the impedance between the wire 5 and the other outside wire, there is no difference in potential at any given instant between the ends of the wire 5, and it follows that no current flows through said wire 20 and hence no energy is transmitted to the receiver at station A nor to the transmitter at station B.

When B is the transmitting station the current induced in the coil 12 flows through 25 the wire 5 and induces a current in the circuit which includes the receiver at station A. The current transmitted by the wire 5 divides at the windings 3 and 4 and flows in opposite parallel relation through them and 30 through the wires 1 and 2 which thus form one side of the line circuit, the wire 5 forming the other side. The division of the current at the middle points of the windings 3 and 4 prevents any inductive effect and consequently no energy is transmitted to the 35 receiver at the station B nor to the transmitter at station A, while the windings 3 and 4 present no impedance but merely their ohmic resistance to the voice currents.

- 40 According to Fig. 2 the local circuit of the receiver at station A is eliminated and the receiver is interposed serially in the wire 5. In other respects the arrangement shown in Fig. 2 is similar to Fig. 1. The same variation is carried out in the arrangements 45 shown in Figs. 3 to 6, 8, 9, 10 and 12.

The arrangement shown in Fig. 3 introduces a further variation according to which the receiver at station B is bridged across 50 the wires 1 and 2, and is in shunt to an impedance coil 4^a, also bridged across the wires and which takes the place of the winding 4 as the impedance element. In this case it is 55 obvious that when A is the transmitting station there will be no difference in potential at any given instant between the ends of the wire 5 and the voice currents will not, therefore, pass through receiver at station A. The receiver at station B will be actuated however. When B is the transmitting station, there will be no difference in potential at 60 any given instant between the ends of the shunt in which the receiver at that station is arranged; hence the energy will be transmitted to the receiver at station A, but will

not be transmitted to the receiver at station B.

In Fig. 4 the transmitter and battery 6 at station A are bridged across the wires 1 and 2 and are in shunt with an impedance coil 3^a also bridged across said wires, and which takes the place of the winding 3 shown in Figs. 1-3. This figure also shows a further variation in the connection of the set at station B, according to which the transmitter and battery 10 of that station are in series in the wire 5 in a substation arrangement otherwise similar to that of Fig. 3. As in the preceding instances, when A is the transmitting station there is no difference of potential at any given instant between the ends of the wire 5. When B is the transmitting station there is no difference of potential at any given instant between the ends of the shunt in which the receiver of station B is arranged, similarly to the arrangement shown in Fig. 3; in a like manner there is no difference of potential at any given instant between the ends of the shunt in which the transmitter of station A is arranged. Hence the energy originating at station B will be transmitted to the receiver at station A, but will not be transmitted to the receiver at station B nor to the transmitter of station A.

Fig. 5 shows the transmitter and battery 10 of station B in series with the wire 5 in an arrangement otherwise similar to that of Fig. 2.

Fig. 6 shows an arrangement similar to that of Fig. 2, except that the receiver at station B is of the three-terminal type and is arranged serially in the wires 1 and 2; and the wire 5 has its end at station B connected to the middle point of the receiver windings which thus constitute the impedance element. In this case the receiver will provide a low impedance path for the alternating currents originating at the same station, providing its windings be perfectly coupled and of the same impedance.

In the circuits of Figs. 1-6, each substation has its local battery for supplying current to the line. Figs. 7, 8 and 9, however, show circuits in which the current supplied to the transmitters is provided by a common battery 14, serially arranged in the wire 5.

In Fig. 7 the wires 1 and 2 at station A are connected by an induction coil 3^b, and the transmitter at that station is connected in shunt with this coil by taps so arranged as to secure the requisite transformer action in transmitting from station A to station B. As shown, the shunt in which the transmitter at station A is arranged has its taps taken from the middle point of the winding 3^b and from the middle point of one of the halves of this winding. In any case a condenser 15 is in series with the coil 3^b between the taps of the transmitted shunt in order to divert the steady current from the

battery 14 with full effect through the transmitter at station A. The wires 1 and 2 at station B are connected by an impedance winding in any of the ways described, the arrangement of Fig. 1 where the receiver of station B is inductively related to the circuit of the line being shown. The wire 5 is connected to the middle points of the windings at both stations in order that there may be no difference in potential between its ends at any given instant when transmitting from station A to station B. At station A the wire 5 divides the windings of coil 3^b into two halves which, in transmitting from station B to station A, are without transformer and, therefore, oppose no impedance to the flow of the telephonic currents over the wire 5. The transmitter at station B is connected in shunt with an induction coil 12^a arranged serially in the wire 5, the taps of the shunt, of course, being taken so as to secure the requisite transformer action in transmitting from station B to station A. A condenser 16 is in series in the bridge across the taps of the shunt in order to divert the battery current through the transmitter at station B.

Figs. 8 and 9 show the circuit in connection with a two-button transmitter in series with the wires 1 and 2 at station A, and which constitutes the impedance element, the wire 5 being connected to the middle or diaphragm terminal of this transmitter and the transmitter at station B being in series in said wire. In Fig. 8 the receiver of station B is connected to the wires 1, 2 and 5 in the same manner as in Fig. 6, whereas in Fig. 9 it is inductively related to the line circuit similarly to the arrangement shown in Fig. 1. As in the previous instances, the impedance between the wire 5 and one of the outside wires is equal to the impedance between the wire 5 and the other outside wire. The circuits of Figs. 8 and 9 are theoretically not so efficient as the circuits of the preceding figures since when station B is transmitting some of the energy will be dissipated in the two button transmitter of station A. However, this disadvantage will not be noticeable in most of the conditions of practice, particularly where the lines are short. The specific circuit arrangements of Figs. 8 and 9 have been made the subject matter of another application filed in my name, Serial No. 321,890, filed September 5, 1919.

Figs. 10, 11 and 12 are schematic examples of circuits having the characteristic features above set forth and in which mechanical repeaters are employed where it may be desirable to augment or amplify the voice currents.

In Fig. 10 repeaters are provided only at the transmitting ends. The transmitter and battery 6 of station A are in a local circuit

with the repeater receiver element 17; and the primary winding of the induction coil by which an E. M. F. is impressed on the line is in another local circuit with the repeater transmitting element 18 and a battery 6^a, the secondary winding of the coil being connected to the wires 1, 2 and 5 in the manner shown in Fig. 1. The wires 1, 2 and 5 and the receiver at station B may be connected up in any of the ways previously described, the arrangement of Fig. 1 being shown. At this station the transmitter is in a local circuit with the battery 10 and repeater receiving element 19; and the repeater transmitting element 20 is in series in the wire 5 together with the line battery 14^a. When transmitting from station A, the repeater as actuated by the telephone transmitter impresses an amplified E. M. F. upon the primary winding of the transformer and the current induced in the line flows in the manner above described, the energy being dissipated in the distant receiver of station B but not being transmitted to the receiver of station A. When transmitting from station B an amplified E. M. F. is impressed directly upon the line, and since the secondary windings of the induction coils offer parallel opposing paths to the resulting current, the receiver of station A alone will be energized and no energy will be transmitted to the receiver of station B nor to the transmitter of station A.

In Fig. 11 repeaters are provided at the receiving ends only. At station A the telephone receiver is in a local circuit with the battery 21 and the repeater transmitting element; and the repeater receiving element is in series in the wire 5; while at station B the telephone transmitter is in series in the wire 5 with the line battery 14^a, the repeater receiving element is in a local circuit with the secondary winding of the induction coil and the telephone receiver is in another local circuit with the battery 10^a and the repeater transmitting element.

In Fig. 12 the repeaters are shown at intermediate points of the line which in this instance consists of two three-wire sections distinguished as C and D, and each having the essential circuit characteristics above described. The section C has wires 1^a, 2^a and 5^a and the section D wires 1^b, 2^b and 5^b corresponding to the wires 1, 2 and 5 of the circuits shown in the preceding figures, the wires 1^a and 2^a and the wires 1^b and 2^b being connected at the adjacent ends of the sections by the respective windings of a repeating coil 22, and the wires 5^a and 5^b being connected at the middle point of the corresponding windings of said coil. At the opposite ends of the line the wires 1^a and 2^a and 1^b and 2^b are connected by impedance windings in the manner previously described, the wires 5^a and 5^b, of course, being

connected to the middle points of the corresponding windings. The sections C and D are provided with batteries 23 and 24 arranged serially in the respective wires 5^a and 5^b. The symmetry of the circuit is maintained for transmission from station A, for example, by employing a pair of repeaters 25 whose corresponding elements are bridged in series across the wires 1^a and 2^a, a battery 26 being arranged symmetrically in the bridge which connects the transmitting elements of the repeaters; and for transmission from station B, by arranging the receiving and transmitting elements of a single repeater serially in the respective wires 5^b and 5^a. Coils 28 are arranged serially in the wires 1^a and 2^a between the connections with said wires of the receiving and transmitting elements of the respective repeaters 25; these coils are of low resistance and are so wound on a common core as to offer extremely high impedance to currents which, in transmission from station A to station B, would tend to flow in the outside wires past the connections of said wires with the repeater receiving elements but to offer no impedance to currents which, in transmission from station B to station A flow over the wires 1^a and 2^a as used in parallel for one side of the line.

When transmitting from station A there is no difference of potential at any given instant between the ends of the respective wires 5^a and 5^b; hence the wires 1^a and 2^a are used in series to provide for the operation of the repeaters 25. The induced current originating at station A is confined by the coils 28 to the receiver elements of the repeaters 25 and flows through these elements in their series relation; current being supplied to the transmitting elements by the battery 26, the repeaters are thus effective to impress an amplified E. M. F. upon the primary winding of the coil 22 and the energy is thus transmitted to the receiver at station B in the obvious manner.

When transmitting from station B the wires 1^b and 2^b act in parallel for one side of section D and the wire 5^b acts for the other side; in section C the action is similar. In both sections the current flows through the windings of the several induction coils in a parallel opposing relation and hence no energy is induced in the receiver at station B nor in the transmitter at station A nor in the repeaters 25 of section C due to the presence of current in section D. The flow of current through the wires 1^b, 2^b and 5^b in the manner described energizes the receiver element of the repeater 26 and current being supplied by the battery 23 to the transmitter element of this repeater an amplified E. M. F. is impressed upon the line. As above explained, the coils 28 oppose no impedance to voice currents flowing through the wires 1^a.

and 2^a as thus used in parallel for one side of the line.

It will, of course, be apparent that the features of the invention may be incorporated in circuits embodying various modifications in detail from the circuits above described; these are, therefore, to be considered merely as examples of circuits in accordance with the invention and having in each instance the essential or characteristic features pointed out.

What is claimed is:

1. In a two-way signaling system, a line circuit comprising two outside branches and a central branch, a transmitting device and a receiving device associated with said line circuit at each end thereof, an impedance element in each of said branches, said impedance elements having such values that signaling current flows through only two of said branches when signals are being transmitted in one direction and flows through all three branches when signals are being transmitted in the opposite direction, and a receiving device coupled to that branch through which no current flows for transmission in one direction.

2. In a two-way signaling system, a line circuit comprising two outside branches and a central branch, a transmitting device and a receiving device associated with said line circuit at each end thereof, an impedance element in each of said outside branches, said impedance elements having such values that signaling current flows through only two of said branches when signals are being transmitted in one direction and flows through all the branches when transmitting in opposite direction, one of said receiving devices being coupled to that branch through which no current flows for transmission in one direction, said other receiving device being coupled serially to those branches that contain the signaling current when the transmission occurs through only two of said branches.

3. In a two-way signaling system, a line circuit comprising two outside branches and a central conducting path, an inductance at each end of said circuit, said outside branches being serially connected at their ends by said inductances, a transmitter inductively coupled to one of said inductances, a receiver inductively coupled to the other of said inductances, and a second transmitter and second receiver in said central conducting path, one of said receivers receiving substantially none of the transmission energy from one of said transmitters.

4. In a two-way signaling system, two substations, a line circuit therebetween comprising two outside branches and a central conducting path, a transformer, a second transformer, said branches being serially connected at their ends by windings of said

transformers, said central branch being connected to an intermediate point of said windings, connections whereby signals from one of said substations is impressed on said 5 outside branches in series relation, and connections whereby signals from the other of said substations is impressed on said outside branches in parallel relation, the impedance of said outside branches and said 10 windings being such that said substations are anti-side tone.

5. In an electric system, a plurality of substation sets, a three-conductor circuit terminating at one end in one of said sets and at the other end in a second of said 15 sets, means for coupling the transmitter of one of said sets to one of said conductors, means for coupling the receiver of a second set to the same conductor, means for coupling the receiver of the first set to the other two conductors, and means for coupling the transmitter of the second set to said two other conductors, said means being so adjusted as to render said sets anti-side tone.

25 6. A two-way signaling system comprising a plurality of signaling sets, a three-conductor circuit terminating at one end in one of said sets and terminating at its other end in a second of said sets, each set comprising a transmitter and a receiver, an impedance at each end of said circuit, said impedances being connected serially with two of said conductors, the transmitter of said first set being coupled with one of said 30 impedances, the receiver of the second set being coupled to the other of said impedances, the receiver of said first set and the transmitter of the second set being coupled to the third conductor of said circuit, said 35 third conductor being so connected to intermediate points of said impedances that said sets are anti-side tone.

7. A two-way signaling system comprising a plurality of signaling sets, each comprising a transmitter and a receiver, a three-conductor circuit terminating at one end in one of said sets and terminating at its other end in a second of said sets, means for coupling one transmitter to said circuit where- 40 by currents therefrom are impressed se-

rially on two of said conductors, means for coupling the transmitter of the second set to said circuit whereby currents therefrom are impressed on the two conductors in parallel, and means for coupling the receiver of the first set and the receiver of the second set to said circuit whereby said sets are anti-side tone.

8. In a signaling system, an impedance element, a signaling line having one end connected to a terminal of said element, a second signaling line having one end connected to the other terminal of said element, a second impedance element joining the opposite ends of said lines, a third line connecting intermediate points of said impedances, a signaling set at one end of said lines and comprising a transmitter and a receiver, means for impressing signals from said transmitter upon said lines in such a manner that the points where said third line is connected to said impedance elements are at the same potential for said currents, said receiver being coupled to said third line whereby said receiver receives none of the signals from said transmitter, a second signaling set at the other end of said lines and comprising a transmitter and a receiver, the transmitter of the second set being coupled to said third line, and the receiver of said second set being so coupled to said second impedance that said second receiver receives none of the signals from the second transmitter.

9. In a signaling system, two substations, a line circuit therebetween comprising two outside branches and a central conducting path, a repeater connected across said branches and having input and output terminals, and an inductance having a winding connected between said input terminals and said output terminals, said inductance having a high impedance for currents flowing serially in said branches but having a low impedance for currents flowing in parallel in said branches.

In witness whereof, I hereunto subscribe my name this 2nd day of September A. D., 1919.

KENNETH S. JOHNSON.
